[57] **CLAIM**

The ornamental design for an outdoor lighting fixture including pivotable support, as shown and described.

DESCRIPTION

FIG. 1 is a top perspective view of an outdoor lighting fixture including pivotable support showing my new design;

FIG. 2 is a front elevation view;

FIG. 3 is a rear elevational view;

FIG. 4 is a bottom plan view;

FIG. 5 is a left side elevational view;

FIG. 6 is a right side elevational view; and,

FIG. 7 is a top plan view.

The supporting plate is shown in broken lines for illustrative purposes only and forms no part of the claimed design.
